MAURICE HAROLD BROWN, OF NORTH BALTIMORE, OHIO.

HORSE-COLLAR CAP.

Application filed November 19, 1924. Serial No. 750,934.

This invention relates to improvements in horse collar caps or pads and a method of producing the same. Most collar manufacturers demand a collar cap which is exceptionally hard and stiff, such a cap being produced by molding the blank of leather from which the cap is formed, under high pressure, whereby the material is compressed to such a degree that it will, as stated, be exceptionally hard and stiff. Such a cap, however, presents the disadvantage, namely, that in riveting the cap to the collar, the rivets are liable to break through the cap, thereby rendering the same unfit for use. This is due to the fact that it is necessary that the heads of the rivets be, as nearly as possible, flush with the inner surface of the cap as otherwise they will rub the horse's neck and cause sores, and it is essential, therefore, that the rivets be applied with a considerable degree of force, under which the cap is liable to break down with the result stated. Attempts have heretofore been made to overcome this difficulty by employing a cheaper grade of leather or subjecting the leather blank to less pressure at the time of molding the cap, but such caps are, of course, not acceptable to the better class of manufacturers. Therefore, the present invention has as its object to provide a cap which may be formed under such degree of pressure that it will possess any desired degree of hardness and stiffness such as demanded by the manufacturer, and will, at the same time, be adapted to be riveted to the collar without any likelihood whatsoever of the rivets breaking through the cap, so that the rivets may be applied with practically the same facility as though the cap were of a softer and more pliable nature than that demanded.

Another object of the invention is to evolve a novel method whereby a cap, possessing the advantages above outlined, may be conveniently produced at a low cost and, in fact, at no greater cost than that involved in the production of the ordinary cap which presents the disadvantages referred to.

Another object of the invention is to provide a novel mold whereby collar caps embodying the present invention may be readily produced.

In the accompanying drawings:

Figure 1 is a perspective view of one form of collar cap embodying the invention, the horse collar with which it is to be associated, being shown in broken lines.

Figure 2 is a vertical sectional view taken substantially on the line 2-2 of Figure 1, and illustrating the cap riveted to the collar.

Figure 3 is a view similar to Figure 1, illustrating a slight modification of the invention.

Figure 4 is a longitudinal sectional view through another modified form of cap.

Figure 5 is a group perspective view illustrating one form of mold which may be employed in producing the cap shown in Figure 1.

Figure 6 is a vertical sectional view taken substantially on the line 6-6 of Figure 5, looking in the direction indicated by the arrows, and illustrating the mold members assembled with the molded cap in place between them.

Figure 7 is a view taken substantially on the line 7-7 of Figure 6.

Figure 8 is a plan view of one of the die members of a mold employed in producing the cap shown in Figure 3.

Figure 9 is a vertical sectional view illustrating a mold employed in producing the cap shown in Figure 4, the cap being shown in position between the mold dies.

In the drawings, the numeral 1 indicates the collar cap which is, as usual, of substantially anticlastic form and which comprises the usual upwardly directed front portion 2 and the rear portion 3, and the depending side portions or flaps 4. Ordinarily, in the manufacture of horse collar caps, leather blanks cut to proper marginal contour, are subjected to pressure in a mold so as to impart to the blanks the desired form and, at the same time, so compress and compact the leather comprising the blanks as to render the leather exceptionally stiff and hard, the general demands of the manufacturers of horse collars being that the caps purchased by them shall possess these qualities.

As heretofore explained, however, such a cap presents the disadvantage that, in fastening the same to the collar, if the securing rivets are so firmly driven as to bring their heads substantially to the surface of the cap, the rivets will break through the cap, thereby rendering the same unfit for use. The cap embodying the present invention is likewise molded under pressure to the required form, but the method of the present invention differs very materially from the method heretofore followed in that whereas here-

tofore it has been customary to exert high pressure against all portions of the area of the cap so that the same will be of uniform density and hardness throughout its entire area, the blank, by the method of the present invention, for a definite portion of its area, is not subjected to pressure, thereby providing the finished product with an uncompressed and comparatively soft portion through which the necessary securing rivets may be readily secured and into which the heads of the rivets may be forced and their heads brought substantially flush with the surface of the cap. This portion of the cap, illustrated in Figures 1 and 2 of the drawings, is indicated by the numeral 5, and in this embodiment is of substantially rectangular outline and extends with its longer dimension transversely of the cap substantially at the juncture of the front portion 2 of the cap with the intermediate portion thereof. Referring now to Figure 2, it will be observed that the rivet, which is indicated by the numeral 6, is adapted to be readily secured through the portion 5 of the cap inasmuch as this portion is of substantially the same density as that of the original blank, which blank, before compression, is more or less pliable. It will also be observed by reference to the said Figure 2, that when the cap is riveted to the flap of the collar, which flap is indicated by the numeral 7, the heads of the rivets 6 may be brought substantially flush with the surface of the uncompressed portion or area 5 of the cap, thereby insuring against any rubbing of the horse's neck to cause sores, which is liable to occur where the rivet heads project to a greater or less extent beyond the surface of the cap. It will be observed by reference to Figure 1, that the dimensions of the uncompressed portion 5 are such that this portion is adapted to accommodate two or more rivets, usually two, which are all that is necessary to secure the cap to the collar.

In that embodiment of the invention illustrated in Figure 3 of the drawings, the cap, which in this figure is indicated in general by the numeral 8, and which is in itself of the same form and same degree of stiffness and hardness as the cap previously described, is subjected to pressure except for two or more circular areas or portions which are indicated by the numeral 9, which areas or portions are left uncompressed and therefore, possess the original softness of the blank from which the cap is formed. These circular portions 9 are, of course, located and arranged in accordance with the proposed location and arrangement of the securing rivets, each rivet being secured through an individual one of the said portions, and the heads of the rivets, in the riveting operation, being brought close to the surface of the respective portions, as in

the first described embodiment. It will be understood, of course, that the invention is not limited to the number of uncompressed portions which may be provided in the cap, as this will depend upon the number of rivets to be employed in securing the cap to the collar.

Figure 4 of the drawings illustrates another embodiment of the invention and in this figure, the cap indicated in general by the numeral 10, is of the same form and possesses the same degree of stiffness and hardness as the previously described caps. However, in this embodiment, pressure is exerted, during the molding operation, against the under side of the cap but no obstruction is present, during the molding operation, at the upper side of the cap, so that the uncompressed portion, which is indicated by the numeral 11, is offset upwardly, thereby providing a shallow recess 12 at the under side of the cap, in which the head or heads of the rivet or rivets may be accommodated, thereby bringing them well within the surface of the under side of the cap as a whole. The uncompressed portion 11 may have the general shape of the portion 5 of the first described embodiment of the invention, or it may have the shape of the uncompressed portions 9 of the embodiment shown in Figure 3.

Figures 5, 6 and 7 of the drawings illustrate the molding or forming dies which are employed in producing the caps shown in Figures 1 and 2 of the drawings, and in the said Figures 5, 6 and 7, the die members are indicated, one by the numeral 13 and the other by the numeral 14. These members need not differ materially from the ordinary molding die members which are employed in the manufacture of horse collar caps, except in the respects which will be pointed out. The upper side of the die member 13 is provided with a forming surface 15 which is of anticlastic form, and the under side of the die member 14, indicated by the numeral 16, is of corresponding form, so that when a blank of leather is placed between the members and the members are brought together and pressure exerted, in the manner and under the conditions attending the molding or shaping of the ordinary collar cap, the leather blank will be caused to assume the desired contour. Ordinarily, however, the pressure exerted upon the leather blank is substantially uniform throughout all portions of the area of the blank and is sufficiently great to insure of the completed article being exceptionally hard and stiff throughout all portions of its area. In accordance with the present invention, and in this embodiment thereof, the molding face of the die member 13 is formed with a recess or depression 17 which is of a contour and dimensions corresponding

substantially to the contour and dimensions of the uncompressed portion 5 with which the completed cap is to be provided, and this recess is, furthermore, of a depth somewhat greater than the distance at which the surface of the portion 5 of the cap is located beyond the under surface of the cap. It will now be evident that when the leather blank is disposed between the die members 5 and the die members are brought together in the usual manner, all portions of the area of the blank will be compressed to a degree to render the completed article exceptionally hard and stiff, except that portion of the 10 blank which extends over the open side of the recess 17 is not subjected to compression. As a consequence, as a result of the molding or forming operation, all portions of the leather blank will have been subjected to great pressure except that portion through which the rivets are to be secured and consequently this portion will retain its 15 original soft and readily penetrable qualities.

Figure 8 of the drawings, illustrates a die member 18 which does not differ materially from the member 13 except that instead of being provided with a substantially rectangular recess in its forming face, it is provided with circular recesses or depressions 20 19 which are of such dimensions and so arranged and located that the cap formed by the use of this die will be provided with the uncompressed portions 9 heretofore described and shown in Figure 3 of the drawings.

The mold or forming die shown in Figure 9, comprises die members 20 and 21 corresponding to the members 13 and 14 of the

first described form, and in this structure, 40 the member 20 is provided upon its forming face with a relatively shallow boss 22, and the member 21 is provided in its corresponding face with a relatively shallow recess 23 which, however, is deeper than the boss 22. 45 The boss 22 and the recess 23 are so located that when the die members are brought together they will be opposite each other and consequently, a leather blank disposed between the die members and acted upon thereby will be provided with the offset uncompressed portion 11 and recess 12 heretofore described and as shown in Figure 4 of the drawings.

Having thus described the invention, what 55 I claim is:

1. A horse collar cap of compressed leather having a substantially uncompressed portion for the passage of a securing element.
2. A horse collar cap of compressed leather having a substantially uncompressed portion providing a relatively shallow projecting portion presented at the under side of the article for the passage of a securing element therethrough.
3. A horse collar cap of highly compressed leather, the upper surface of which cap is substantially smooth, the cap having a portion of its area substantially uncompressed to afford a relatively soft portion one side of which is presented at the under side of the cap and through which portion a fastening element may be readily secured with its head substantially embedded in the 70 said side of the portion.

In testimony whereof I affix my signature.

MAURICE HAROLD BROWN. [L.S.]
